UNITED STATES PATENT OFFICE.

STANLEY W. NICHOLSON, OF TOLEDO, OHIO, ASSIGNOR, BY MESNE ASSIGNMENTS, TO
THE DURA COMPANY, OF TOLEDO, OHIO, A CORPORATION OF OHIO.

WINDOW REGULATOR.

Application filed September 25, 1924. Serial No. 739,897.

The invention relates to window regulators and refers more particularly to mechanisms for raising and lowering windows of vehicles. One of the objects of the invention is the provision of an improved window regulator which may be cheaply manufactured and readily installed. Other objects are the provision of a mounting plate for the window regulator which is so shaped that it may be formed from a blank with the minimum waste of material; and the provision of a pivotal lifter arm which is so shaped that its pivotal portion is in substantial alignment with its points of connection to the window and to the member for actuating the lifter arm. Further objects are the provision of a window lifter of the screw drive type having an improved nut for connecting the screw to the lifter arm and also having an improved universal coupling for rotating the screw.

With these as well as other objects in view, the invention resides in the novel features of construction and combinations and arrangements of parts as more fully herein-after set forth.

In the drawings:

Figure 1 is an inside elevation, partly broken away, of a vehicle door having applied thereto a window regulator embodying my invention;

Figure 2 is a vertical section therethrough;

Figure 3 is a plan view of the lifter arm;

Figures 4 and 5 are inside elevations of the sections of the nut for connecting the screw to the lifter arm;

Figure 6 is a sectional elevation showing the universal coupling for connecting the screw to one of the drive shafts and also showing the manner of securing one of the drive gears upon the latter shaft;

Figure 7 is a plan view of a blank from which the mounting plate is formed.

In the present instance I have shown my window regulator as applied to the door 1 of a vehicle which has in its upper portion the opening 2 and in its lower portion the chamber 3. 4 is the window or closure which is vertically slidable in the side uprights of the door from a position closing the opening 2 into the chamber 3.

5 is the mounting plate for the mechanism of the window regulator, this mounting plate being a gusset extending across a cor-

ner between one of the side uprights of the door and the lock board 6 and secured at its ends to this side upright and the lock board by suitable means such as the screws 7. 8 is the lifter arm pivotally mounted at 9 upon the lower portion of the mounting plate 5 and provided at its outer or free end with the roller 10 which is engageable in the channel 11 secured to and depending from the lower edge of the window. 12 is the screw for swinging the lifter arm, the threaded portion of this screw engaging the nut 13 which is pivotally connected to the lifter arm. 14 is the gear box housing the gears 15 and 16, the shaft of the former being connected to the handle 17 upon the inner side of the door and the shaft of the latter extending transversely of the first shaft and being connected to the upper end of the screw 12 by the universal coupling 18. This gear box is formed in two sections having their meeting edges in the plane of the axis of the shaft carrying the gear 16 and the sections are secured together by rivets which connect the gear box to the mounting plate. 19 is the window counter-balancing spring having its lower end connected to the lifter arm 8 and its upper end adjustably connected to the mounting plate 5 near the upper end of the latter. As specifically shown the mounting plate is provided with the elongated openings 20 which are alternatively engageable by the hook 21, which in turn is engageable by the hook 22 secured to the upper end of the counter balancing spring.

23 is a bumper formed of suitable material such as rubber and located upon the bottom sill of the door to engage the outer or free end of the lifter arm 8 when the latter is in its lowermost position. This bumper is so positioned that the channel 11 upon the window clears the bumper and as a consequence the weight of the window remains upon the roller 10 of the arm.

As shown particularly in Figure 3, the lifter arm 8 is laterally bent near its pivotal end so that its pivotal portion 24, which is engageable with the pivot 9, is in substantial alignment with the centers of the roller 10 and the nut 13 whereby when force is applied through the screws 12 to raise or lower the lifter arm, tendency of the lifter arm to turn laterally or in a path parallel to the axis of its pivot is negligible.

The nut 13 is formed of the sections 25 and 26 each having a pivot portion 27. The pivot portion of the section 25 is journeled in the lifter arm itself while the pivot portion of the section 26 is journeled in the bracket 28, the foot flanges of which are secured to the lifter arm by suitable means such as rivets. These nut sections 25 and 26, as shown particularly in Figures 4 and 10 5 have their threads so positioned that one section may be readily used with the other and assembled with either end uppermost. Furthermore, either section is interchangeable with another section of the same type 15 all of which facilitates the assembly. To maintain the sections in proper relation to the screw 12 and at the same time to take care of wear of the screw threads there is the spring washer 29 located between the 20 bracket 28 and the adjacent section 26 tending to force this section toward the other section.

The hook which is secured to the lower 25 end of the counterbalancing spring 19 engages in an aperture in the bracket 28, this aperture being in substantial alignment with the pivotal portion of the lifter arm and the centers of the nut and roller connected to the lifter arm whereby the force exerted 30 by the counterbalancing spring has no appreciable tendency to laterally turn the lifter arm.

As shown particularly in Figure 6, the universal coupling 18 is formed of a section 35 of rod, the end portions 30 and 31 of which are flattened at right angles to each other and respectively engage between the bifurcations 32 and 33 of the shaft 34 and screw 12 respectively. These flattened end portions are pivotally connected to the bifurcations by suitable means such as the rivets 35, the outer ends of which are preferably made hollow so that they may be more readily peened over. The gear 16 is secured upon 40 the shaft 34 by knurling the shaft to form longitudinal threads 36 thereupon and then by forcing the gear upon these threads which cut into the gear and hold the latter from rotation upon the shaft. To firmly 45 hold the gear 16 from longitudinal movement upon the shaft 34 I have provided the annular beads 37 upon the gear near its ends and corresponding annular grooves 38 in the shaft, the beads engaging in the 50 grooves. These beads are preferably formed by peening inwardly the ends of the gear.

As shown particularly in Figure 7, the mounting plate 5 is so shaped as to provide

at its ends securing portions 39 and 40 for receiving the screws which secure the mounting plate to a side upright and the lock board of the door respectively, a portion 41 near one end for securing the gear box 14 thereto, an adjacent laterally enlarged portion 42 in which the elongated openings 20 60 are formed and also a portion 43 near the opposite end for receiving the pivot 9 for the lifter arm, this mounting plate being furthermore shaped so that it may be formed from a blank 44, which is in the 70 form of a flat metallic strip, with the minimum waste of material. As shown this blank is of a width to form two mounting plates arranged side by side and reversed end for end, the severed edge 45 of the side 75 upright securing portion 39 of each mounting plate being parallel to the severed edge 46 of the lock board securing portion 40 and the severed transversely extending edge 47 at the inner end of the side upright securing portion 39 being parallel to the severed 80 transversely extending edge 48 of the laterally enlarged portion 42. The intermediate severed edges 49 of the mounting plate extend parallel to each other. As a consequence, zig-zag severing of the blank longitudinally thereof, forms the blank into two 85 mounting plates with the minimum waste of material.

What I claim as my invention is:

1. In a window regulator, the combination 90 with a support, of a lifter arm pivoted upon said support and connected to a window, and means connected to said lifter arm for swinging the same, said lifter arm being laterally bent so that its point of pivotal connection, its point of connection to the window, and its point of connection to its actuating means are in substantial alignment.

2. In a window regulator, the combination 100 of a lifter arm pivotally supported at one end and connected to a window at the other end, an actuating member connected to said lifter arm intermediate its ends, and a counterbalancing spring also connected to said 105 arm intermediate its ends, said lifter arm being laterally bent so that its point of pivotal connection, its point of connection to said window, its point of connection to said actuating member, and its point of connection to said counterbalancing spring are in substantial alignment.

In testimony whereof I affix my signature.

STANLEY W. NICHOLSON.
